(57) **CLAIM**

The ornamental design for a dental mixing tip nozzle, as shown and described.

DESCRIPTION

FIG. 1 is a perspective view of the new design;
FIG. 2 is a front elevation view thereof;
FIG. 3 is a rear elevation view thereof;
FIG. 4 is a left side elevation view thereof, the right side being omitted since the right side is symmetrical to the left side;
FIG. 5 is a top plan view thereof; and,
FIG. 6 is a bottom plan view thereof.
